ASH RECEIVER

Andrew T. Hagerty, Elkhart, Ind., and John L. Mohun, Chicago, Ill., assignors to The Adlake Company, a corporation of Illinois

Application January 2, 1936, Serial No. 57,198

22 Claims. (Cl. 206—19.5)

The invention relates to ash receivers adapted to be fitted within a wall, such as the rear face of a car seat back or the side wall of the car.

The object of the invention is to provide a conveniently located ash tray for the use of the smoker, associated with a normally closed receptacle which may be tilted for emptying by an attendant.

A preferred embodiment of the invention is hereinafter described, and is illustrated in the accompanying drawings, in which

Fig. 1 is a detail face view in perspective of a wall equipped with the ash receiver and to which it is secured;

Fig. 2 is a plan section on the line 2—2 of Fig. 3;

Fig. 3 is a face view of the parts shown in Fig. 1, portions of the receiver and wall being broken away;

Fig. 4 is a sectional view on the line 4—4 of Fig. 1; and

Fig. 5 is a similar view, the receiver being in open or discharging position.

A portion of a wall, which may be that of a room or of a car seat back, is shown at 10, and is apertured for the entry of the casing 11 of the ash receiver, the front face of which is provided with a frame 12 for surrounding the wall aperture and overlapping the adjacent portions of the wall, and serving as a convenient means for attaching the device to the wall as by means of screws 13.

An ash receptacle 14 is normally housed within the casing 11, its front face 15 overlapping the side and bottom members of the frame 12, and being hinged to the bottom member of the frame 12, as shown at 16. The receptacle 14 is shown as oblong rectangular in plan section, and as of less height than the opening of the frame 12, in order that it may be tilted forward for emptying of its contents, as shown in Fig. 5. This receptacle is held within the casing by a suitable latch, which preferably takes the form of a spring 17, attached to the rear wall of the casing and 45 having a shoulder 18 for hooking over the rear wall of the receptacle.

A plate 19 extends across the upper portion of the frame opening, and is carried by a pivot rod 20, mounted between the upper portion of 50 the side walls of the casing. This plate extends downwardly below the upper margin of the front wall of the receptacle 14, and cooperates with the upper portion of this wall to provide a tray for receiving the ashes deposited thereon by the user.

In order to provide a suitable tray for this

purpose a central panel 21 of the front plate 15 of the receptacle 14 is shown as being inclined forwardly and upwardly, and terminating at its upper margin as an upwardly and outwardly inclined lip 22. The side margins of the panel 21 and the lip 22 are connected with the body of the front wall of the receptacle by webs, as 23. The lower end of the plate 19 curves outwardly, as shown at 24, making contact with the panel 21 at the base of its lip 22 and with this lip providing an ash tray of ample capacity. The plate 19 is normally held in contact with the panel 21, and against the upper portions of the sides of the frame 12, by the action of a spring 25, coiled about the pivot rod 20 and reacting between the plate 19 and a fixed portion of the casing.

The plate 19 is provided with a suitable handle, as 26, by which it may be swung inwardly to open the tray and permit the ashes accumulated thereon to fall into the receptacle 14.

This plate may also serve as a convenient means for releasing the detent 18 from engagement with the receptacle to permit the dumping of the latter, the spring 17 being continued upwardly and inclined forwardly, as indicated at 27, and being so positioned that it will be engaged by the plate 19 when the latter is forced backwardly approximately to the limit of its movement, the detent 18 being thereby disengaged from the receptacle. The upper end of the spring comes into frictional engagement with the top wall of the casing 11 as shown in Figs. 4 and 5. The pressure of the backwardly moving plate 19 will tend to bow backwardly the upper portion of the spring and also cause it to slide along the top of the casing. The friction developed by the latter movement adds to the resistance offered by the spring without requiring an unduly heavy spring which would cause an unpleasant reaction upon release of pressure on the plate 19.

The side members of the frame 12 may be provided with downwardly facing shoulders, as shown at 28, under which the side portions of the receptacle front 15 engage.

Preferably a cushioning spring 29 is provided for yieldingly seating the receptacle within the casing, to prevent rattling and the accidental disengagement of the detent 18.

Various changes in the details of construction may be made within the scope of the invention as defined in the appended claims, as, for example, the configuration of the walls of the ash tray and of the detent for holding the receptacle in closed position.

We claim as our invention—

1. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, and a plate pivotally attached across the upper portion of the frame opening to swing inwardly and being of such extent as to engage the inner face of the front wall of the receptacle adjacent the lower margin of its outwardly inclined portion.
- 10 2. An ash receiver comprising a frame plate for surrounding a wall aperture, an upwardly open receptacle of less height and width than the frame aperture, its front wall overlapping the side and bottom members of the frame and being pivotally attached to the bottom member of the latter, and a plate pivotally attached across the upper portion of the frame opening to swing inwardly, the lower portion of such plate being inclined outwardly and engageable with the front wall of the receptacle.
- 20 3. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, and a plate pivotally attached across the upper portion of the frame opening to swing inwardly, the lower portion of such plate being inclined outwardly and engageable with the front wall of the receptacle.
- 30 4. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, and a plate pivotally attached across the upper portion of the frame opening to swing inwardly, said plate being of such extent as to engage the inner face of the front wall of the receptacle adjacent the lower margin of its outwardly inclined portion.
- 40 5. An ash receiver comprising a frame plate for surrounding a wall aperture, an upwardly open receptacle of less height and width than the frame aperture, its front wall overlapping the side and bottom members of the frame and being pivotally attached to the bottom member of the latter, a plate pivotally attached across the upper portion of the frame opening to swing inwardly, the lower portion of such plate being inclined outwardly and engageable with the front wall of the receptacle, and releasable means cooperating with the receptacle for positively locking the same in closed position.
- 50 6. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, a plate pivotally attached across the upper portion of the frame opening to swing inwardly, the lower portion of such plate being inclined outwardly and engageable with the front wall of the receptacle forming a closure.

portion of such plate being inclined outwardly and engageable with the front wall of the receptacle, and releasable means cooperating with the receptacle for positively locking the same in closed position.

7. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, a plate pivotally attached across the upper portion of the frame opening to swing inwardly and being of such extent as to engage the inner face of the front wall of the receptacle adjacent the lower margin of its outwardly inclined portion, and a detent for locking the receptacle in closed position, said detent being so located as to be moved by the last-named plate when swung inwardly for releasing said receptacle from closed position.

8. An ash receiver comprising a frame plate for surrounding a wall aperture, an upwardly open receptacle of less height and width than the frame aperture, its front wall overlapping the side and bottom members of the frame and being pivotally attached to the bottom member of the latter, a plate pivotally attached across the upper portion of the frame opening to swing inwardly, the lower portion of such plate being inclined outwardly and engageable with the front wall of the receptacle, and a detent for locking the receptacle in closed position, said detent being so located as to be moved by the last-named plate when swung inwardly for releasing said receptacle from closed position.

9. An ash receiver comprising a frame plate for surrounding a wall aperture, an upwardly open receptacle of less height and width than the frame aperture, its front wall overlapping the side and bottom members of the frame and being pivotally attached to the bottom member of the latter, the upper portion of such front wall being inclined outwardly and upwardly, a plate pivotally attached across the upper portion of the frame opening to swing inwardly, the lower portion of such plate being inclined outwardly and engageable with the front wall of the receptacle, and a detent for locking the receptacle in closed position, said detent being so located as to be moved by the last-named plate when swung inwardly for releasing said receptacle from closed position.

10. An ash receiver comprising a casing adapted to fit within a wall aperture and having an open front face and a frame plate surrounding such face, an ash receptacle of less height than the casing and being pivotally attached to the bottom member of the frame plate, the front wall of the receptacle having an outstanding lip at its upper margin, a depending plate pivotally attached across the upper portion of the open face of the casing and normally engaging the inner face of the front wall of the receptacle adjacent the inner margin of the lip, a spring detent secured to the casing and engageable with the receptacle when closed, such detent being so located as to be moved by the depending plate when swung inwardly to release said receptacle.

11. In an ash receiver, in combination, an apertured wall plate, a frame fitted to the wall plate in the aperture, a receptacle pivotally attached to the lower member of the frame, the front wall of the receptacle forming a closure.

for the lower portion of the frame opening and having an outstanding lip at its upper margin, a plate pivoted adjacent the upper member of the frame to swing inward, the plate being of such extent that its lower margin may engage the inner face of the front wall of the receptacle to form with its outstanding lip an ash tray.

12. In an ash receiver, in combination, an apertured wall plate, a frame fitted to the wall plate in the aperture, a receptacle pivotally attached to the lower member of the frame, the front wall of the receptacle forming a closure for the lower portion of the frame opening, a swinging plate depending from the upper portion of the frame, the plate being of such extent that its lower margin may engage the inner face of the front wall of the receptacle below the upper margin thereof, and being so shaped as to form with said front wall an ash-receiving pocket.

13. An ash receiver, comprising in combination, a chambered casing adapted to fit within a wall aperture and having an open front, a receptacle pivotally mounted within the casing to swing forwardly and downwardly out of the casing, the front wall of the receptacle terminating below the top of the casing, a closure for the space above such front wall and pivoted to the upper portion of the casing to swing inwardly, the lower portion of the closure and the upper portion of the front wall of the receptacle being so shaped as to form an ash tray when engaged.

14. In an ash receiver, in combination, a chambered casing having an open front, a receptacle movably mounted in the casing to swing forwardly and downwardly, a leaf spring extending forwardly and upwardly from the rear of the casing and having a shoulder for engaging over the rear wall of the receptacle, the upper end of the spring frictionally engaging the top of the casing, and a manually controlled releasing element for disengaging the shoulder from the receptacle.

15. In an ash receiver, a frame having a large opening, an upwardly opening receptacle of less height than the hole in the frame, means to mount the receptacle on the lower portion of the frame to swing outwardly and downwardly from a position within the opening of the frame, a tray plate normally engaging the receptacle to receive ashes and form a closure for the receptacle and means to mount the plate on the upper portion of the frame to swing inwardly and discharge the contents of the tray into the receptacle.

16. In an ash receiver, a frame having a large opening, an ash receptacle hinged to swing between a receiving position in the opening of the frame and a substantially inverted discharge position, a tray plate, resilient means mounted on the receiver to hold the tray plate normally in position to close the receptacle, and a latch for holding the receptacle in receiving position and so located as to be released by movement of the tray plate from normal position.

17. In an ash receiver, a frame having a large opening, an ash receptacle mounted to swing between a receiving position in the opening of the frame and a substantially inverted discharge

position, a movable tray plate normally closing the receptacle, and latch means cooperating with the receptacle to hold it in receiving position and so located as to be released by movement of the tray plate from normal position.

5

18. In an ash receiver, a frame having a large opening, an ash receptacle having a front wall of less height than the opening, means mounting the receptacle on the frame to swing between a receiving position in the opening of the frame and a substantially inverted discharge position, means for holding the receptacle in receiving position, and a tray plate cooperating with the opening to close the same and with the front wall of the receptacle to form a tray and movable relative to the receptacle to discharge the contents of the tray into the receptacle.

19. In an ash receiver, a frame having a large opening, an ash receptacle having a front wall of less height than the opening, means mounting the receptacle on the frame to swing between a receiving position in the opening of the frame and a substantially inverted discharge position, means for holding the receptacle in receiving position, and a tray plate cooperating with the opening to close the same and with the front wall of the receptacle to form a tray and movable relative to the receptacle to discharge the contents of the tray into the receptacle, and movable further to release the holding means.

25

30

20. In an ash receiver, a frame having a large opening, an ash receptacle hinged below the opening to swing between a receiving position in the opening of the frame and a substantially inverted discharge position, a latch for holding the receptacle in receiving position and a depending tray plate carried by the frame above the receptacle in receiving position to form a tray and movable relative to the receptacle to discharge the contents of the tray into the receptacle.

35

21. In an ash receiver, a frame having a large opening, an ash receptacle hinged below the opening to swing between a receiving position in the opening of the frame and a substantially inverted discharge position, a latch for holding the receptacle in receiving position and a tray plate hinged to the frame to swing from a forward position in contact with the receptacle to form an ash-receiving tray to a removed position in engagement with the latch to release the receptacle.

45

50

22. In an ash receiver, a frame having a large opening, an ash receptacle having an outwardly directed front wall portion, means for mounting the receptacle to swing between a receiving position in the opening of the frame and a substantially inverted discharge position, a movable tray plate having an outwardly and downwardly directed portion normally cooperating with the outwardly directed wall of the receptacle to form an ash tray, resilient means for holding the tray plate in its normal position and a latch for holding the receptacle in its normal receiving position, said latch being so located as to be released by withdrawal of the tray plate.
